UNITED STATES PATENT OFFICE.

JAMES H. MANN, JR., OF MONT EAGLE, TENNESSEE, ASSIGNOR TO SOUTHWESTERN SALES CORPORATION, OF NEW YORK, N. Y., A CORPORATION OF DELAWARE.

COIN-DETECTING VENDING MACHINE.

Application filed February 27, 1924. Serial No. 695,485.

This invention relates to vending machines, and more particularly those employing eliminating devices for the rejection of spurious coins or the like to operate the same.

5 A vending machine to perform its function properly should not only be dependably operable when a standard coin or the like is inserted, but should in addition perform two other functions. The one such function 10 should be to detect and eliminate all spurious coins and tokens, etc. The second such function should be that such detection or elimination should leave the machine in a condition for operation with subsequent introduction 15 of a standard coin or the like. The latter two features constitute important improvements in the art attainable by means of the present invention.

Again it is known that other means of illegal operation are possible. Methods to avoid such action have been disclosed in my prior United States Patent 1,408,112, in connection with which, the present application is to be considered as forming a continuing improvement. However, certain modifications have been necessary by virtue of the non-jamming action now introduced working in conjunction with the novel spurious coin detector 20 eliminator and segregator. Again, in devices of the above kind it is of considerable importance that the more or less intricate working parts should be easily and separately replaceable. To this end therefore, starting with the casing, a removable back or 25 mounting plate is provided so that practically the entire device is removable from said back plate after releasing the locking mechanism. The back or mounting plate only is affixed to a wall or the like, by means of screws, which 30 screws become hidden and out of reach when the casing is assembled on the plate for normal working.

In addition thereto an important feature comprises the locking cover which is demountable and easily removable. This is important for the art described, since if an attempt has been made to tamper with the lock, or the indirect locking means for the casing controlled thereby, it requires a simple effort for the attending inspector to replace the lock by a suitable interchange without disturbing the rest of the mechanism. It will be described hereafter how the casing and back plate are so arranged that tamper-

ing with the lock or its spring bolt can only affect the rest of the mechanism in an unimportant way. This independence of control is made an important feature, especially in connection with the slide or door provided for giving access to the coin chamber at the bottom of the casing or housing. Such slide is preferably arranged to extend up to, but is not attached to, the locking cover. An offset or hooking lug occurs at the top of the slide for opening or closing such coin chamber. Thus in attempting to pry open the cover or top, the slide or door control is not affected thereby immediately. The entire cover needs to be removed before the control becomes visible and operable. Nevertheless, with the cover off it becomes possible entirely to remove the slide, for it not only is arranged to function as a coin chamber control, but is also arranged to displace a locking latch that is normally operated when the merchandise is depleted. This latch locks the coin control delivery mechanism in such a position that the entering slots for the coins, or the like, no longer become possible. In this way the public does not become defrauded. To replenish the merchandise magazine therefore, not only must the merchandise delivery tray be unlocked and brought back to normal position, but the coin slot control must also be allowed to go back to normal. Thus attending inspector on removing the cover must first lift up the slide to uncover the coin chamber, but thereafter on returning the slide to its original position, mechanism on the slide automatically releases the lock referred to and the magazine can then be filled with the required merchandise. It should be borne in mind that sometimes an attempt may be made to bend or displace that portion of the slide covering the opening to the coin chamber. Then again the lock removing mechanism on the slide may become weak calling for a replacement of the slide control. By means of the present invention this becomes possible without necessarily having to take away the entire device for overhaul.

In the same general manner it will be found that all the more important and intermediate mechanisms making up the device are arranged to be replaceable, and easily demountable practically without any tools being required.

The present disclosed type of coin con-

trolled vending machine comprises in its general function an important method for operating the same. The old type of blocking chute is done away with, and in its place is introduced a novel form of coin detecting, eliminating and segregating chute, which latter leads to the coin control device proper for actuating the vending tray. However, it is not enough merely to add the new feature to the old, for in operating the eliminating mechanism it is particularly advisable to control the coin entering slot of the device so that during elimination the slot becomes closed to further introduction of coins or the like, till the chute or merchandise delivery mechanisms are cleared. In this way the purchaser as well as the machine itself is safeguarded. This important result is attained by having the actuator bar (introduced for the delivery of the merchandise after the proper coin or token has been inserted) articulating with the eliminator mechanism and with the coin slot closing shutter. Since the actuator bar operates a dog and ratchet holding device through articulation therewith, once the delivery tray is tilted at all the actuator bar and therefore the coin shutter, etc., is forced to continued one-way action, thus giving the necessary safe-guarding assurance. A considerable change has therefore been necessary to attain the new and important function of the device; thus both during elimination and delivery of merchandise the slot shutter is operated. Should, however, the merchandise be exhausted then it will be found that not only does the eliminator remain locked in its operative position, but the coin shutter is also closed. This type of operation is of importance when an attempt is made to operate the mechanism with the introduction of two coins (nickels for example) before the actuator bar is pushed upwardly. Should this transpire and only one piece of merchandise be available in the machine, not only will the device become locked, by virtue of the elimination device being in operating position but the added coin and the merchandise will both be delivered at one and the same time.

In order to emphasize the above objects, and more clearly to bring out the advantages accruing from the invention, the following drawings are attached and made part of the specification, in which:

Fig. 1 is a perspective view of the casing.

Fig. 2 illustrates a rear view of Figure 1.

Fig. 3 corresponds to Figure 2 with back or mounting plate removed to show construction of casing.

Fig. 4 is a front view of the frame with slider plate removed.

Fig. 5 is a rear view of Figure 4.

Fig. 6 illustrates a front assembly view of the frame structure.

Fig. 7 is a rear view of Figure 6.

Fig. 8 is a detail view of the movable plate. Figs. 9 and 10 illustrate front and rear views of the back or mounting plate.

Fig. 11 is an edge view of the slider plate employed. 70

Fig. 12 is a perspective view of the coin chamber partitioning means.

Figs. 13 and 14 illustrate bottom views of the cover plate in locked and unlocked positions. 75

Figures 15 and 16 are edge views of Figures 13 and 14.

Fig. 17 is a detail perspective view of the bolt plate.

Fig. 18 discloses an elevation of the magazine. 80

Fig. 19 is a bottom view of Figure 18.

Fig. 20 gives a plan view of the structure with cover removed.

Fig. 21 illustrates the construction of the coin chamber slider control. 85

Fig. 22 illustrates the construction of the actuator bolt.

Fig. 23 is a back view of the slide plate.

Figs. 24 and 25 give detail views of the ratchet sector employed. 90

Figure 26 is a fragmental detail section taken on the line 26—26 of Figure 6;

Figures 27 and 28 are respectively side elevations of Figure 6 showing the movable plate in closed and open positions. 95

It will be seen that within the casing 1 there is preferably inserted an easily removable frame 2 held in place by means of a removable magazine 3 fitting against the upper portion of the frame and the supporting ears 4 for a merchandise delivery tray 5. The lower portion of the frame 2 rests upon a coin chamber partitioning means 6 which latter is first inserted in the casing 1 and forms at the bottom of the casing both a spurious coin or token delivery opening 7, as well as a coin chamber having a coin collecting slot 8 on the lower side of the casing. Cooperating with the side of the frame 2 opposite to the magazine is a demountable mounting plate 9 which not only closes the back wall of the casing but is a means for readily attaching the casing with its merchandise and frame, etc., to a wall or the like, upon which the mounting plate is to be secured. The mounting plate is secured upon its mounting by screws passing through holes 10 which screws are covered by the attached casing. 105

The frame has a central channel 11 communicating with a diameter detecting chute 12—12, one for each side of the frame. A cover piece 13 properly machined to size is attached to the frame by means of screws 15 or the like, such that when a detachable movable or eliminating plate 16 is mounted thereon (as best seen in Figure 8) with its edge contacting flanges or lips 17 lying over the beveled lower wall of the chutes 12, the 110

115

120

135

diameter standard for the coins or tokens is set. Should the specimen inserted at the ends of the slots 12, which slightly flare outwardly, (matching with the coin introducing slots 18 of the casing) be deficient in size the top edge of the coins will fall outwardly forcibly so that without the movable plate being finally drawn away from the frame 2 such spurious specimen will fall out outside the frame and movable plate, to be delivered through the opening 7 at the back of the delivery shelf 19 forming a bottom wall of the casing.

The actuation of the movable plate is brought about by the motion of a cam plate or slide 20 embracing the front or magazine side of the frame. Such slide is provided with a tooth 21 passing through an actuator bar 22 and the slotted frame 2, and is locked to such bar by means of the loop end of a spring 23 whose other end is attached to the frame as at 24. By means of the slot 25 the cam plate is moved upwardly and downwardly in such manner that wedges 26 pass under the movable plate 16 and so cause the latter to oscillate by virtue of the fingers 27 and 28 of the movable plate slidably entering the appropriate slots 29 and 30 of the frame.

It will be noticed that additional openings 31 and 32 occur in the frame plate, which latter act as slots for fingers 33, 34 integral with the cam plate or slide. Their function is to dislodge any irregularly shaped token entering the slots 12 and becoming wedged in place and thereby choking the channels and precluding further functioning. To avoid the latter contingency on moving the actuator bar 22 upwardly it necessarily causes the wedge-shaped fingers to engage with such token and force the latter toward the delivery opening 7 as the movable plate is being actuated. The movable lips 17 of the movable plate aid in this action.

The chute 11 normally leads to the standard coin segregating chute 35 leading to the coin actuated merchandise delivery mechanism. Part of the latter has already been described in my previous United States Patent 1,408,112. There is therefore no need for going into great particulars regarding the same. Suffice to say that a novel tray catch 36 is provided, freely pivoted in the wall of the frame 2, in such a way that the knurled shank 37 of the catch extends entirely through the frame in order that a milled leaf spring 38 on the coin-box shutter-control (Fig. 21) 39 may engage with such knurled shank to actuate the catch when the last package of merchandise has been vended and the tray 5 becomes caught by the overbalance catch 36 which holds the rotated tray in locked position. (See especially Figure 4.)

The standard coin on entering the vending chute 40 falls between a boss 41 and the wall 65 of a rotatable lever plate 42. The boss 41

is made part of a toothed sector meshing with rack teeth 44 on the actuator bar 22. Thus as the actuator bar is moved upwardly the standard coin forms the necessary mechanical link for causing the lever plate to rotate and with it the tray 5, by virtue of enmeshing elements at one end of the tray structure. Such structure carries integrally therewith a mutilated gear plate 46 meshing with co-acting radially arranged slots 47 of a one-way retaining ratchet plate 48, held by a movement completing pawl 49, spring pivoted on the frame 2. Thus as the ratchet plate or sector 48 moves counter-clockwise (when viewed from the front of the frame structure) it is automatically held in its advanced position till the complete movement is accomplished, when the sector rides past the one face of the pawl to allow the latter to swing out of locking action and thereby the sector 48 is enabled completely to return. The forward motion of the sector 48 is caused, upon the insertion of a proper coin, by the edge 52 of the rotatable lever plate 42 starting the sector 48 through pressure on lug 50. However, as soon as sector 48 has advanced enough so that movement completing pawl 49 has engaged one-way retaining ratchet plate 48 the coin falls into the coin receptacle and rotatable lever plate 42 returns to its normal position, due to spring action, and exerts no further influence during the operation. The sector 48, however, is now partially rotated but is held against backward movement by pawl 49. A downward extended lug "Y" of the sector 48 has been thrown, due to the movement just described, into the path of edge "X" of the actuator 22. Then upon further movement or completion of the stroke of actuator 22 edge "X" will strike and force lug "Y" of sector 48 through its entire movement thus completing the forward operation after which the entire mechanism will be allowed to return to its normal or operating position.

If then on coin actuation the ratchet sector 48 causes the tray 5 to rotate, should the last piece of merchandise be vended, the catch 36 will fall and drop behind the back 53 of the tray and it will require the lifting and return of the shutter control 39 with its leaf spring 38 to bring the catch into upright position so that the magazine 3 may be filled and the device put into normal operation again.

Along the chute 11 other spurious coin and token devices are arranged. Thus it is possible to employ slugs that shall have the diameter of the standard coin (which latter in this case may be a nickel). Should a steel blank be employed then by virtue of a magnet 53 mounted on the movable plate and opposite the chute 11 such magnetic material will be attracted to one side and preferably held in place till the movable plate is forced to act, when the magnetic material will be auto-

matically discharged and eliminated as hereinafter set forth. To direct the blank toward the magnet a boss 54 is introduced into the channel 11. On the other hand as soon as the movable plate is actuated extensions 55 on the back plate, passing between the legs of the magnet, disengage the specimen from the surfaces of the magnet by virtue of the movable plate simultaneously approaching the back plate at the time that it recedes from the frame 2.

In addition to the above there is also employed an under weight detecting device arranged in the path of the same channel. This comprises a weighted bell crank lever 56 having its one end in the path of the chute 11 and so placed as to tend to arrest a spurious specimen at a curve 57 of the chute. Thus with operation of the slide 20, the lever 56 is tilted by contact of the offset 59 with the arm 60 and the arrested insert released. The movable plate is tilted at an angle and the walls of the channel comprising chute 11 and chute 35 will be spread or separated to such an extent that the arrested insert will be dislodged from the point of the lever 56, and thus bypassed out of the path of the segregating chute 35. In some instances as with oblong slugs or the like it is possible for the specimen to become lodged between the projecting end of the bell crank lever and the curve of the chute 57. For continued operation of the vending device the bell crank lever 56 is provided with a projection 58 which is normally in the path of the slide 20 so that by virtue of an offset 59 the weighted arm 60 will be raised and thereby draw the projecting end into a releasing position and ready for a further contingency. It is to be remembered that such release here referred to cannot take place normally till the movable plate is operated by the actuator bar 22.

In the construction of the movable plate note needs to be made of a bevelled deflecting extension 61 which aids in directing the fall of short diametered specimens from the path of chute 12. In addition to the above the plate carries a revolubly mounted spearing device 62 having its head 63 extending through the surface of the plate and slightly into the path of the central channel or chute 11. The object of the device is to catch perforated specimens such as washers or the like whether made of iron or lead, etc. It is a feature of such weighted fingering device that once a perforation is struck the head 63 of the finger tends more and more to enter into the perforation by virtue of the weight of the specimen itself. Should it transpire that such a perforated slug has been fed to the machine, it will be caught by the spearing device and only released with the actuation of the movable plate as a whole. The revolubly mounted head 63 will then be moved upwardly by the device 62 contacting with the mounting

plate so as to release the speared specimen and then allow the same to fall outside of the chute 11 to be delivered up to the opening 7 at the bottom of the casing.

In the construction of the back plate attention is also directed to the novel type of interweaving locking device provided for. It will be observed that offset lugs 64 and 65 occur on the back plate for engaging under the upper surfaces 66, 67 of the back of the casing. In addition a movable offset lug 68 integral with a sliding bolt 69 occurs to engage with the same upper surface 66 on the one side of the casing. On the other hand an abutment 69' is made integral with the back plate for permitting the one end of the locking bolt to fasten itself between the top of the slotted member at 66 and abutment 69' on the back plate. The lower end of the back plate has a parallel offset 70 that also fits under the upper edge 71 of the lower portion of the back casing. It thus becomes clear that with the insertion of the back plate in the manner indicated and with the bolt 69 shifted into place that the housing structure of the casing becomes locked as a unit. The sliding movement of the back plate for dismemberment only becomes possible with the withdrawal of the bolt 69 by means of the finger piece 72 integral therewith. The upper portion of said bolt is preferably arranged with a pin extension or the like 73 working in a slot 74 of the lip 75 forming an offset to the plate 9. Similarly there is preferably formed a lip 76 and an offset lug 77 for the better guidance of the bolt 69.

In the assembly of the device there is first introduced at the portion of the casing the coin chamber partitioning member 6 having a perforated rib 78 made integral therewith for the guidance of an operating bolt 79 whose end 80 is grooved to engage with the slot 81 of the bar 22. Thereafter the shutter slide 39 for the coin chamber and carrying its leaf spring, is inserted by means of the bent over end 82 of the same, which latter should be flush with the top of the casing. The frame assembly is then made which includes the movable plate and slide and introduced into the casing, proper spacing with the latter being effected by subsequent introduction of the merchandise magazine 3. The back plate can be put on and the finger piece 72 pushed into position for locking the casing housing as a whole. In this condition the lock cover is to be attached and the machine made ready for use. However it is by no means desirable in devices of the present kind to employ any type of lock. The possibilities and incitement for tampering are so large and the attendants charges so great that it is equally important for commercial success that the number of steps employed to "make ready" be reduced to an absolute minimum.

To the above end the locking cover is made

up in such a manner that proper covering cannot be effected without the two main coverings are properly in place. The latter are respectively the coin shutter slide and the 5 mounting plate when properly locked into place. With the second step the locking on the cover per se is produced only intermediately by means of a spring bolt in the key controlled lock.

10 Turning therefore to the locking cover it will be seen that two lugs or catches 83 and 84 are provided for engaging respectively with an offset 85 on the casing on the one hand, and an offset 75 on the back plate on 15 the other hand. It is the right hand end of the back plate that is to be engaged at this time. However, the lug 84 cannot enter into place without the finger piece 72 being pushed home into bolt locking position with 20 respect to the casing proper. Thus the attendant is automatically reminded that proper inspection and replacement has not been made. Secondly, on attempting to put the cover further into place the 25 attendant will be encountered with the tell-tale of obstruction 82 in the way, should it transpire that the shutter slide to the coin chamber has not operated effectively to close the same. With everything in order 30 therefore the cover will fit on and the intermediate locking plate 86 be enabled to come under the lugs 87 on the casing and 69' on the back plate and so give adequate locking protection to the casing housing as a whole.

35 The intermediate locking plate 86 has at one end a lug 88 which is arranged to hold the lock spring bolt 89 in retarded position, when the locking plate is withdrawn by the spring 90 from its locking position under the 40 lugs 87 and 88. The latter is the normal unlocked position of the locking cover and is indicated by means of a teat 91 extending through the cover plate by virtue of a slot 92 therefor. Thus when all is assembled and 45 the proper shutter and back plate adjustments have been made it is possible not only to replace the cover fittingly upon the casing housing but in addition thereto, by means of the teat 91 outside of the cover, to slide the bolt plate into locking position with the lugs 50 87 and 88 permitting the spring bolt 89 of the spring lock to snap into plate and effectively lock the intermediate locking bolt

plate into position with respect to the casing wall, the back plate and the shutter slide, etc. 55 On unlocking the spring lock by means of an appropriate key entering into the keyway 93 the spring 90 automatically withdraws the bolt plate 86 and the contents can be examined whether for replenishment of the 60 magazine 3 or obtaining the coins collected at the bottom of the device or for repair, etc.

In operation on inserting a coin in the slots 18 the detecting devices are automatically operated and with the movement of the actuator bolt 79 the movable plate allows the spurious coins to drop directly toward the delivery opening 7. In case a plurality of magnetic slugs are deposited before the bolt 79 is pressed upwardly for the delivery of 70 the merchandise it will be found that the boss 54 does not permit of one token to pass by the other held by the magnet in its attraction. Thus on pressing the bolt 79 upwardly the movable plate causes an immediate evacuation 75 of all spurious tokens together with possible delivery of merchandise if the proper standard coin should happen to enter the coin controlled delivery tray mechanism. Should the actuator bar be held up in its 80 path for one reason or another the slots 18 for the coin inserts become automatically covered up by means of wings or shutters 94 and 95 formed on each side of the slider so that the public as well as the device is adequately safeguarded. 85

Having thus described the nature of my invention what I claim is:

In combination, a frame, a coin-completing mechanical drive, a coin detecting chute 90 formed in the wall of the frame, and an oscillating plate, means to arrest spurious inserts in said chute, and means to dislodge and by-pass said arrested inserts from said chute and away from the coin completing mechanism. 95

and an offset thereon, said flanges operating the oscillating plate to spread it away from the adjacent wall at an angle thereto and said offset operating the 100 arresting means to dislodge the arrested insert, and means to actuate said plate and to restore it to normal position.

In testimony whereof I have hereunto set my hand.

JAMES H. MANN, JR.
